UNITED STATES PATENT OFFICE.

EDMOND LAURENT, OF HELLEMES-LILLE, FRANCE.

STEAM-GENERATOR.

1,315,024.

Specification of Letters Patent.

Patented Sept. 2, 1919.

Application filed June 4, 1919. Serial No. 301,739.

To all whom it may concern:

Be it known that I, EDMOND LAURENT, citizen of the French Republic, residing at 32 Rue Victor Hugo, at Hellemes-Lille, 5 Nord, in the Republic of France, have invented new and useful Improvements in Steam-Generators, of which the following is a specification.

This invention relates to improvements in steam generators which insure a continuous circulation of water, a thorough combustion and a methodical heating. In its preferred embodiment a steam generator constructed according to this invention comprises a cylindrical body one end of which is close to the furnace while the feed takes place at its other end, and boilers or lower drums arranged in chambers successively traversed by the furnace gases and connected to the 15 cylindrical body by tubular nests divided each into two groups, the group nearest to the feed opening into the bottom of the cylindrical body and the group farthest away rising to a certain height into the said 20 body.

The two tube groups in each cluster may be separated one from the other in the said cylindrical body by a cross partition and the tubes opening into the bottom of the 25 said body may extend downwardly into a given depth in the boilers, the other tubes being connected to the upper part of these boilers.

Owing to this arrangement, the feed water 30 entering the apparatus at the farthest end of the furnace at a place where gases are cooler will be compelled to circulate from the main boiler body through the tubes and the lower boilers in order to reach after a 35 rapid and natural circulation the top of the furnace at a very high temperature and thoroughly purified. The production of steam is greatly enhanced by this arrangement; and the gases are thoroughly utilized 40 from their starting point in the furnace until they are discharged through the chimney.

In the accompanying drawings, given by way of example:

50 Figure 1 shows a longitudinal vertical section of a steam generator constructed according to this invention.

Fig. 2 is a corresponding cross section.

Fig. 3 is a longitudinal section of another arrangement. 55

Fig. 4 is a cross section of a steam generator with two cylindrical bodies.

Fig. 5 is a longitudinal section of a steam generator with stepped boilers.

Fig. 6 is a longitudinal section of a steam 60 generator comprising several transverse cylindrical bodies.

Fig. 7 shows a steam boiler having an inner flue with which is combined a tubular cluster arrangement according to this in- 65 vention.

Fig. 8 is a detail showing an arrangement insuring the decantation of the steam boiler feed water.

The steam generator shown in Figs. 1 and 70 2 comprises a cylindrical body or shell C divided into four compartments by cross partitions 6. Under this cylindrical body C, are arranged transversely three boilers or lower drums 3, 4, 5 placed in the chambers 3', 4', 5', which communicate with each other through their upper ends. The chamber 3' is constituted by the chamber proper 75 of the furnace F situated at one end of the boiler and the chamber 5' communicates with the flue 7 leading to the chimney, the three chambers being thus successively traversed by the hot gases.

The water is fed to the steam boiler at 8 in the most distant compartment from the furnace by a 80 pipe descending close to the bottom of the steam boiler. It will be seen in the drawings that the boilers or drums 3, 4, 5 communicate with the body C through nests of pipes comprising each a part 1 situated 85 beyond the partitions 6 with respect to the direction of the water circulation in boiler C and a part 2 situated on the other side of such partition. The tubes 1 of each cluster open thus into the coldest part of the corresponding compartment of the boiler and the tubes 2 of this cluster open into the hottest part of the preceding compartment. The tubes 2 open into the lower part of the steam boiler while the tubes 1 rise to a certain height in this boiler. It 90 will be readily understood that the described arrangement insures a rapid circulation of water and a perfect utilization of the heat evolved from the gases. 95

The tubular clusters of the lower boilers 100

4, 5 are shown as divided into two groups by partitions 6^a corresponding to the partitions 6 whereby the gases are properly guided. The boiler 3 is close to the masonry wall which separates the chambers 3', 4' and its tubular cluster is traversed by the furnace gases. This cluster could likewise be divided into two groups by a partition.

Fig. 3 shows a slightly modified construction 10 wherein the cylindrical body C projects directly above the furnace F. This figure shows likewise that the tubes 2 may project a certain distance into the lower boilers.

The invention is not limited to the above 15 described arrangements. For instance two boilers similar to the boilers 3 of Fig. 1 could be arranged in the furnace chamber 3'.

As shown in Fig. 4, two boiler bodies C, 20 C' may also be connected to the same transverse drum B. One drum could likewise be combined with more than two cylindrical shells.

The lower drums may also be placed at 25 different levels as shown in Fig. 5.

In this figure the partitions 6 and 6^a are omitted. The boiler C is supported, in this case, at any intermediate point of its length by a wall M which allows the gases to pass 30 thereabove, a lower drum being located in the chambers situated on either side of this wall.

According to Fig. 6, the plant comprises 35 four parallel cylindrical bodies C, C¹, C², C³ connected each to a boiler or drum by a cluster arranged like the clusters above described. These cylindrical bodies are connected together by pipes T, T' which insure proper communication between the various 40 cylindrical bodies for steam and water respectively.

Fig. 7 shows how the efficiency of an existing boiler C with an internal flue can be increased by arranging in the furnace chamber F a boiler B connected by a nest of tubes 1, 2 to a cylindrical body or upper boiler C¹. The two lower boilers communicate with the upper boiler C through the tubes 10 and 11 respectively.

Fig. 8 shows that by arranging in the boiler suitable baffle partitions 9 the decantation of the feed water can be effected.

The lower boilers might be connected together by pipe lines, the cylindrical bodies 55 could be provided with flues traversed by the hot gases and generally various changes may be made in the arrangements shown or described without departing from the nature of this invention.

Having now described my invention what I claim as new and desire to secure by Letters Patent is:

1. A steam boiler comprising in combination an upper cylinder having one end in 65 proximity to the furnace, feed-water admis-

sion means at the opposite end of said cylinder, chambers in communication with said furnace and adapted to be successively traversed by the furnace gases, lower drums in 70 said chambers and nests of tubes connecting the lower drums to the upper cylinder, each of said nests comprising two adjacent groups of tubes, the tubes in the group nearest to the feed end of the boiler opening into and stopping at the bottom of the cylinder 75 and the tubes in the other group in each nest extending into the body of the cylinder above the bottom thereof.

2. A steam boiler comprising in combination an upper cylinder having one end in 80 proximity to the furnace, feed-water admission means at the opposite end of said cylinder, chambers in communication with said furnace and adapted to be successively traversed by the furnace gases, lower drums in 85 said chambers and nests of tubes connecting the lower drums to the upper cylinder, each of said nests comprising two adjacent groups of tubes, the tubes in the group nearest to the feed end of the boiler opening into and stopping at the bottom of the cylinder 90 and the tubes in the other group in each nest extending into the body of the cylinder above the bottom thereof, and transverse partitions in the cylinder between the two groups 95 of tubes in each nest.

3. A steam boiler comprising in combination an upper cylinder having one end in proximity to the furnace, feed-water admission means at the opposite end of said cylinder 100, chambers in communication with said furnace and adapted to be successively traversed by the furnace gases, lower drums in said chambers and nests of tubes connecting the lower drums to the upper cylinder, each 105 of said nests comprising two adjacent groups of tubes, the tubes in the group nearest to the feed end of the boiler opening into and stopping at the bottom of the cylinder and the tubes in the other group in each nest extending into the body of the cylinder above the bottom thereof, cross walls in the cylinder 110 between the two groups of tubes in each nest and partitions between the two groups of tubes in each nest, in the part thereof 115 which is located in the aforesaid chambers.

4. A steam boiler comprising in combination an upper cylinder having one end in proximity to the furnace, feed-water admission means at the opposite end of said cylinder, chambers in communication with said furnace and adapted to be successively traversed by the furnace gases, lower drums in 120 said chambers and nests of tubes connecting the lower drums to the upper cylinder, each 125 of said nests comprising two adjacent groups of tubes, the tubes in the group nearest to the feed end of the boiler opening into and stopping at the bottom of the cylinder and extending downward into the corresponding 130

lower drum and the tubes in the other group in each nest extending into the body of the cylinder above the bottom of the cylinder and opening into the top of the corresponding lower drum.

5. A steam boiler comprising in combination an upper cylinder with an inner flue having one end in proximity to the furnace, a lower drum and an upper drum located 10 in the furnace chamber, pipes connecting the upper and lower drums to the upper and lower part of the cylinder, respectively, and a nest of tubes connecting the upper and lower drums to each other, said nest comprising two adjacent groups of tubes, the 15 tubes in one group opening into and stopping at the bottom of the upper drum and the tubes in the other group extending into the body of the upper drum above the bottom thereof.

6. A steam boiler comprising in combination an upper cylinder having one end in proximity to the furnace, feed-water admis-

sion means at the opposite end of said cylinder, chambers in communication with the 25 furnace and adapted to be successively traversed by the furnace gases, lower drums in said chambers and nests of tubes connecting the lower drums to the upper cylinder, each of said nests comprising two adjacent groups 30 of tubes, the tubes in the group nearest to the feed end of the boiler opening into and stopping at the bottom of the cylinder and the tubes in the other group in each nest extending into the body of the cylinder above 35 the bottom thereof, and deflectors adapted to form a vertically sinuous path for the feed water in the feed end of the upper cylinder.

In testimony whereof I have signed my 40 name to this specification in the presence of the subscribing witness.

EDMOND LAURENT.
